(57) **CLAIM**

The ornamental design for a meat clamp, as shown and described.

DESCRIPTION

FIG. 1 is a perspective view of a meat clamp;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

The broken lines shown in the drawings depict a portion of a meat clamp that forms no part of the claimed invention.
